UNITED STATES PATENT OFFICE

162,703

TELEVISION CABINET

Samuel E. Adler, Chicago, Ill.

Application December 6, 1949, Serial No. 6,431

Term of patent 14 years

Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet, of which the following is a specification, reference being had to the accompanying drawing, forming part thereof.

Fig. 1 is a front elevational view of a television cabinet, showing my new design;

Fig. 2 is a top plan view of the cabinet; and

Fig. 3 is a fragmentary sectional view taken on line 3—3 of Fig. 1.

The dominant features of my design reside in that part shown in full lines in the drawing.

I claim:

The ornamental design for a television cabinet, as shown and described.

SAMUEL E. ADLER.
